Primary Examiner — April Rivas(74) *Attorney, Agent, or Firm* — NZ Carr Law Office PLLC**(57) CLAIM**

The ornamental design for a luggage, as shown and described.

DESCRIPTION

FIG. 1 is a top, front, and right side perspective view of a luggage, showing my new design;

FIG. 2 is a bottom, rear, and left side perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The broken lines depict portions of the luggage that form no part of the claimed design.

1 Claim, 7 Drawing Sheets(56)
